UNITED STATES PATENT OFFICE.

ALBERT J. KECK, OF ST. PAUL, MINNESOTA.

MECHANICAL TOY.

SPECIFICATION forming part of Letters Patent No. 695,058, dated March 11, 1902.

Application filed August 25, 1899. Serial No. 728,408. (No model.)

To all whom it may concern:

Be it known that I, ALBERT J. KECK, a citizen of the United States, residing at St. Paul, in the county of Ramsey and State of Minnesota, have invented certain new and useful Improvements in Mechanical Toys, of which the following is a specification.

This invention relates to toys for children; and it consists in the construction, combination, and arrangement of parts, as herein-after shown and described, and specifically pointed out in the claims.

In the drawings, Figure 1 is a foreshortened elevation, Fig. 2 is a foreshortened plan, and Fig. 3 is a foreshortened sectional side elevation, of the toy. Fig. 4 is a front view of one of the attachments detached. Fig. 5 is an end view, Fig. 6 is a sectional side elevation, and Fig. 7 is a plan view, enlarged, of one of the traveling carriages or cars removed. Fig. 8 is a side view on the same scale as Figs. 1, 2, and 3 of the track portion of the toy folded together as it appears when not in use or when being transported. Fig. 9 is a cross-sectional view, Fig. 10 is a sectional side elevation, and Fig. 11 is a plan view, enlarged, of a modified form of carriage or car, together with a section of the track. Fig. 12 is an enlarged side view of another modified form of carriage or car detached. Fig. 13 is a sectional elevation of one form of the toy, illustrating a modification in the construction. Fig. 14 is an enlarged cross-sectional view, Fig. 15 is an enlarged sectional side elevation, and Fig. 16 is an enlarged plan view, of a section of the track and one of the carriages employed in the modification shown in Fig. 13.

In this invention is comprised an inclined track upon which one or more carriages or cars are arranged to be moved back and forth, the cars or carriages adapted to support figures of human beings, animals, birds, or other objects. The track may be constructed in any suitable manner, but will preferably be in two or more parts A' A² and semitubular in cross-section and hinged together, as at a, so as to be folded together, as shown in Fig. 8, when not in use or for shipment to reduce the space occupied by the track. At one end the track is provided with a base A³, preferably weighted or otherwise arranged to give stability to the lower end of the track, while the other end is

provided with a bracket or plate A⁴ to rest against the wall of a room and support the other end of the track, as shown in Figs. 1, 3, 5, and 13.

At the lower end of the section A' of the track is arranged a cord-sheave B' and a series of smaller idler and carrier or tension sheaves B² B³ B⁴, while similar carrier-sheaves B⁵ B⁶ B⁷ will be arranged in the upper end of the upper section A² of the track, these various sheaves adapted to support and guide an endless cord D, the axle of the sheave B' being provided with a crank-handle B⁸, by which the cord may be run over the pulleys, as shown, when the sheave B' is revolved. By this arrangement the revolution of the crank B⁸ will cause the cord D to travel upward in the upper part of the track-sections A' A² and downward within the lower part, the two "bights" of the traveling cord being shown in Figs. 1, 3, 4, 5, 9, 10, 11, 12, and 13.

To arrange the device, it is unfolded and set with the plate A⁴ at any convenient point against the wall of the room and with the weighted end A³ on the floor at the proper point to bring the two parts A' A² of the track in alignment and with the cord D in proper position around the sheaves. When thus arranged, a device is provided which can be employed in a multitude of ways to amuse, interest, and instruct children. For instance, figures of many different kinds may be connected to the traveling cord and made to move up and down the track as the crank B⁸ is turned backward and forward, or small carriages or cars may be provided adapted to be coupled to the cord and upon which the figures may be placed. These cars or carriages may be provided with coupling devices adapted to be automatically released when the car or carriage reaches a given point on the track and permit the carriage to slide back again down the track by gravity. For the purpose of illustration I have shown several forms of these cars or carriages. In Figs. 1, 3, 5, 6, 7, 12, 13, 14, 15, and 16 the carriage is in the form of a block E', with its lower part projecting into the hollow of the track and with flanged wheels E² running upon the upper edges of the track-sections as rails. Some form of gripping or coupling means will be provided whereby the cars or carriages may

be connected to the traveling cord, and for the purpose of illustration I have shown in Figs. 1, 3, 5, 6, 7, 9, 10, 11, and 12 a simple form of such coupling. This consists of a 5 forked plate b' , pivotally connected at b^2 to the body of the carriage and with the forks embracing the upper bight of the cord D and with a projection b^3 , adapted to be acted on by a spring b^4 to retain the plate either in 10 its closed or open relation. Thus when in its outward position, as in Figs. 1, 3, 5, 6, 7, 10, and 12, the spring will hold the plate b' across the cord at an angle, so that the forks will 15 clamp the cord and cause the carriage to be drawn along by the traveling cord. Then if the plate b' be turned at right angles to the cord, as in Fig. 11, the spring b^4 will retain the plate in that position and keep the forks clear of the cord, so that the carriage will 20 move freely over the cord or the cord will move freely through the forked plate. If, therefore, a stop d be provided at the upper end of the track, against which the outer free end of the plate b' will strike, the forked plate 25 will be thrown over at right angles to the cord and the coupling will be released when the carriage reaches the upper end of the track and will then run back down the track by gravity. This will cause endless amusement 30 and pastime to children and will encourage the exercise of the inventive faculty in inducing them to devise different figures and objects to place upon the carriages. The carriages are shown provided with spring-clips 35 g , between which the objects to be carried by the carriages may be supported.

F' represents a wire frame covered with a thin paper diaphragm F^2 and adapted to be set above the track at any convenient point, 40 so that as the carriage runs down the inclined track and is suddenly stopped at the bottom the figure, as h in Fig. 3, will be thrown through the paper diaphragm.

In Figs. 9, 10, and 11 is shown a carriage 45 having a mechanism for revolving the figures as they are moved up and down the track, consisting of a friction-wheel G' , arranged to run upon the bottom of the track $A' A^2$ and adapted to engage a horizontal disk or frame 50 G^2 , mounted to revolve upon the carriage, and thereby impart a revolving motion to the frame. Thus any figures mounted upon the frame G^2 , as by clips g , will be given a rotating motion at the same time they are moved 55 up or down the tracks $A' A^2$.

In Fig. 12 is shown a "rattle" attachment to the carriage, consisting of a toothed wheel H' upon one of the flanged wheels E^2 and adapted to act upon a spring H^2 , whereby a 60 rattling noise will be made as the carriage moves up and down the track $A' A^2$.

A great variety of different figures and images may thus be utilized and devised.

In Fig. 3 a bell K' is shown at the upper 65 end of the track-section A^2 , against which the carriage will strike at the end of its upward movement, and thus sound the bell.

In the modification shown in Figs. 13, 14, 15, and 16 the cord D is provided with one or more balls or other enlargements m' , adapted 70 to engage a forked catch m^2 on the carriage, and thus carry the carriage along with the moving cord. At the upper end of the track-section A^2 is arranged an incline A^5 , up which the carriage runs to cause the forked plate 75 m^2 to be elevated above the obstruction m' on the cord, and thus release the carriage and allow it to run backward down the inclined track. This forms a very simple and effective automatically-releasable coupling. 80

In Fig. 3 an extension M' is shown connected at one end at M^2 to the lower end of the main track-section and resting by its other end upon the floor, upon which the weighted base A^3 rests to form a continuation of the 85 track A' , whereby means are provided for guiding the carriages from the end of the track to the floor. By this means the carriage when released from the endless carrying-cord will be conducted from the track to 90 the floor and thence across the floor as far as its momentum will carry it.

The endless-cord arrangement provides that the motion may be continuous, so that while one child operates the drum another 95 child or a number of children can find occupation and amusement by placing the carriages upon the traveling cord as it is continuously moving. Thus it will not be necessary to wait for the cord to be at any particular or predetermined position before the carriages are coupled to it, as it would be if the cord were not an endless one, but extended only from end to end of the track.

Having thus described my invention, what 105 I claim as new is—

1. In a mechanical toy, an inclined track having a weight at one end, and supported thereby loosely upon the floor, and with the other end resting loosely against a vertical 110 support, pulleys journaled in the ends of said track, an endless cable engaging said pulleys, and with projections thereon at suitable intervals, a carriage supported upon said track, and with depending catch engaging said cable, and adapted to be engaged by said projection thereon, and an inclined projection upon said track at its upper end adapted to receive said carriage, and cause it to be elevated to disengage said catch from said cable 115 projection, and permit said car to run down said inclined track by gravity, substantially as set forth.

2. In a mechanical toy, a weight resting 125 loosely upon the floor, a standard rising vertically from said weight, a track projecting at an angle from the upper end of said standard, and adapted to be supported loosely by its upper end against a vertical support, a carriage running upon said track, pulleys in the 130 opposite ends of said track, an endless cable running over said pulleys, and with projections at suitable intervals thereon, a catch upon said carriage, and engaging said projec-

tions on said cable, means for actuating said cable, and means whereby said catch may be disengaged from said cable at a predetermined point in its transit, substantially as set forth.

3. In a mechanical toy, a weight resting loosely upon the floor, a standard rising vertically from said weight, a track projecting at an angle from the upper end of said standard, and adapted to be supported loosely by its upper end against a vertical support, a carriage running upon said track, pulleys in the opposite ends of said track, an endless cable running over said pulleys, and with projections at suitable intervals thereon, a catch upon said carriage, and engaging said projections on said cable, means for actuating said cable, and means whereby said catch may be disengaged from said cable at a predetermined point in its transit, a bridging-section connected to the lower end of said track by one end, and resting by its other end upon the floor loosely to form a continuation to said

track at its lower end, and provide means for conducting said carriage from said track to the floor, substantially as set forth.

4. In a mechanical toy, a weight resting loosely upon the floor, a standard rising vertically from said weight, a track projecting at an angle from the upper end of said standard, and adapted to be supported loosely by its upper end against a vertical support, said track formed in two parts and hinged at the lower side of the adjacent ends of the two parts, whereby when extended the two parts will be supported, and capable of being folded together when not in use, substantially as set forth.

In testimony whereof I have hereunto set my hand in the presence of two subscribing witnesses.

ALBERT J. KECK.

In presence of—

J. W. STEVENS,
C. N. WOODWARD.
